UNITED STATES PATENT OFFICE

NORMAN C. HOCH, OF HUNTINGDON, PENNSYLVANIA

INTERNAL COMBUSTION ENGINE

Application filed August 6, 1930. Serial No. 473,414.

The invention relates to internal combustion engines and has for its principal object the provision of an engine that is particularly adapted for driving an aeroplane propeller but capable for use in driving other machinery, and of a type in which the engine cylinders are arranged radially of the crank shaft and provided with oppositely disposed pistons, the motor being of two-cycle type and having means provided for compressing the combustible mixture and delivering it to the cylinders in compressed condition for expansion therein preliminary to compression by the engine pistons to form a combustible mixture.

A further object of the invention is the provision of means for compressing the mixture for introduction to the engine cylinders, said means being actuated by the crank shaft of the engine.

The invention will be described in detail hereinafter and will be found illustrated in the accompanying drawings, in which

Figure 1 is a side view of the engine showing it applied for driving an aeroplane propeller, the propeller being shown fragmentarily and in broken lines.

Figure 2 is a view in elevation of the engine with the front plate of the casing shown in Figure 1 removed,

Figure 3 is a similar view with the rear plate of the casing removed,

Figure 4 is a sectional view on a plane indicated by the line 4-4 of Figure 2,

Figure 5 is a sectional view on a plane indicated by the line 5-5 of Figure 4, and

Figure 6 is a sectional view on a plane indicated by the line 6-6 of Figure 2.

In the drawings similar reference characters are used to designate corresponding parts in all the views.

The engine or motor is enclosed within a casing comprising a cylindrical member 1, to which is secured a conical front plate 2, and a rear plate 3, 4 designating the shaft of the engine on which may be mounted a propeller or other means for utilizing the power of the engine.

Arranged around the crank shaft 4 are

cylinders selected for illustration being four, but it will be apparent that any number of cylinders may be provided and the invention is therefore not limited to the number of cylinders shown. The cylinders have both ends open and are secured to inwardly offset portions 10 bordering openings in the cylindrical member 1, and are also secured or formed integral with a central casing 11 providing the crank case of the engine. In each of the cylinders there is provided two pistons designated 12 and 13, said pistons being arranged to reciprocate in opposite directions from one another so that when the explosive charge in the cylinder is compressed, the pistons will be in the positions shown in Figure 5 in the cylinder 6, and the ignition devices, indicated by the spark plugs 14 are therefore arranged intermediate of the ends of the cylinders for detonating the charge when compressed. The pistons 13 are operatively connected with a crank 15 arranged within the crank casing 11 by means of piston rods 16. Pistons 12 have each a piston rod 17 connecting it with a cross head 18 to the end of which are secured rods 19 slidably mounted in guides 20, and are connected by means of links 21 with other cranks 22 on the crank shaft 4 arranged on the outer side of the crank case 11, and diametrically opposite to the crank 15 within the crank case heretofore described this structure providing for the opposite movement of the pistons, heretofore referred to.

Each of the engine cylinders is provided with intake ports 23 adjacent to its two ends, and exhaust port 24, preferably arranged on the opposite side of the cylinder from the intake port, these intake and exhaust ports being connected with manifolds that will be hereinafter particularly described to introduce the combustible mixture to the cylinders and to discharge the exhausted products therefrom. It will be noted that the exhaust ports 24 are inwardly of the middle portion of the cylinder in each instance from the intake ports, this arrangement of the ports permitting discharge of the exhaust products under compression as result of the explosion in each of the cylinders before the intake

ports are exposed by the movement of the pistons when in the position shown in Figure 5, cylinder 9, and the pistons 12 and 13 are provided with baffles 25 that direct the incoming combustible mixture from the ports 23 toward the middle of the cylinder and thereby prevent the incoming mixture from being forced outwardly through the exhaust ports 24, and in fact this direction of the combustible mixture assists in forcing the exhaust products to the exhaust ports preliminary to the closing of the ports and compression of the combustible mixture when the pistons assume the position shown in Figure 5, cylinder 8, and the extreme compression position as shown by cylinder 6 in said figure.

The combustible mixture for the several cylinders is compressed in separate compression cylinders, one of these compression cylinders being provided for each of the engine cylinders, and for the engine cylinders 6, 7, 8, and 9, there is provided a compression cylinder designated 26, 27, 28, and 29, respectively. The construction and operation of the several compressed cylinders are identical and description of one of them will be sufficient to understand the construction of the others. 30 designates an intake manifold for combustible mixture that may be connected to a carburetor or other supply of a combustible mixture, and having flanges 31 therefrom leading to the several compression cylinders in which is provided a valve casing 32 having a valve 33 for controlling the entrance of the combustible mixture into the cylinder and a valve 34 controlling the supply of the combustible mixture from the compression cylinder through a manifold 35 connected to the intake ports 23. 36 indicates compression pistons in the compression cylinders, said pistons being connected for simultaneous movement by a connecting rod 37. 38 indicates a pitman pivotally secured to the connecting rod 37 as shown at 39, and eccentrically connected to gear wheel 40 that is geared to the gear wheel 41 secured to the shaft 4. 42 indicates another gear wheel also geared to wheel 41 that operates the pistons 36 in the cylinders 27 and 29 by means of a crank 44 on the shaft 43 that is connected to the pistons in said cylinders by a pitman 45. Secured to the shaft 43 and shaft 46 driven by the gear wheel 40 are cams 47, and 48 indicate push rods that ride on the peripheries of said cams and actuate rocker arms 49 to actuate the valves 33 and 34.

The exhaust manifold is shown at 50 and is provided with a number of branches 51 connecting with the exhaust ports 24 in the respective cylinders.

It will be apparent that the engine parts will be so arranged and timed that when the pistons are in the position as shown in Figure 5, cylinder 6, the explosion in the explosion chamber will take place and the pistons will

be moved outwardly as shown by the position of the pistons in cylinder 7, such movement of the pistons being the expansion stroke of the engine. When the pistons reach the position immediately before the position as shown in cylinder 8, the exhaust takes place through the exhaust ports 24 and the intake is immediately thereafter exposed so that the compressed products of combustion in the compression cylinder connected with the engine cylinder will be admitted to the intake ports 23, and when the pistons are returned towards the middle of the cylinder for the compression stroke and the ports 23 and 24 are not exposed between the pistons the products will be compressed and when the pistons assume the position again shown in the cylinder 6 the explosive mixture is again fired. It will be clear that in each cylinder there will be an explosion for each rotation of the crank shaft, and in an engine employing four cylinders as shown in the drawings power is created by the engine substantially equivalent to an eight cylinder engine of the four cycle type.

What is claimed is:

An internal combustion engine, comprising an engine casing, a crank shaft journaled in said casing, a crank casing surrounding said crank shaft, open ended engine cylinders secured to said engine casing and crank casing and arranged radially of the crank shaft, opposed pistons mounted, for reciprocal movement in each cylinder, means connecting said pistons and the crank shaft to reciprocate the pistons, said cylinders being each provided with intake ports and exhaust ports adjacent to the respective ends thereof and controlled by the movement of said pistons, fuel compression cylinders, means to supply fuel to said compression cylinders, means connecting said compression cylinders and the intake ports of said engine cylinders, valves controlling said supply and connecting means, pistons in said compression cylinders, and means operated by said crank shaft to actuate said last mentioned pistons and the valves.

In testimony whereof I affix my signature.

NORMAN C. HOCH.
